US0D1050089S

(12) **United States Design Patent** (10) **Patent No.:** **US D1,050,089 S**
(45) **Date of Patent:** **** Nov. 5, 2024**

(54) **ANTENNA**

(71) Applicant: **Panorama Antennas Ltd.**, London (GB)

(72) Inventor: **Pasi Pun Entaban Anak Watt Lanyau**, London (GB)

(73) Assignee: **Panorama Antennas Ltd.**, London (GB)

(**) Term: **15 Years**

(21) Appl. No.: **29/867,002**

(22) Filed: **Oct. 4, 2022**

(30) **Foreign Application Priority Data**

Jul. 15, 2022 (GB) 6219649

(51) **LOC (14) Cl.** **14-03**

(52) **U.S. Cl.**

USPC **D14/230**

(57) **CLAIM**

The ornamental design for an antenna as shown and described.

DESCRIPTION

FIG. 1 is a front view of an antenna according to my new design;

FIG. 2 is a left side view thereof;

FIG. 3 is a right side view thereof;

FIG. 4 is a top view thereof;

FIG. 5 is a bottom view thereof;

FIG. 6 is a rear view thereof;

FIG. 7 is a perspective view, from the top left corner, thereof;

FIG. 8 is a perspective view, from the top right corner, thereof;

FIG. 9 is a perspective view, from the bottom left corner, thereof; and,

FIG. 10 is a perspective view, from the bottom right corner, thereof.

The broken lines illustrate portions of the article and form no part of the claimed design.

1 Claim, 10 Drawing Sheets
